STREET CLEANER

Charles T. Link, Jr., Skokie, Ill., assignor to Elgin Sweeper Company, Elgin, Ill., a corporation of Illinois

Application August 11, 1955, Serial No. 37,414

Term of patent 14 years

(Cl. D14—3)

FIG. 1

FIG. 2

Figure 1 is a top plan view of a street cleaner showing my new design; and

Figure 2 is a side perspective view thereof.

The side opposite that shown in Figure 2 is similar to the one shown; and the dotted line disclosure of wheels are for illustrative purposes only.

I claim:

The ornamental design for a street cleaner, substantially as shown and described.
